United States Patent Office

Des. 227,785
Patented July 17, 1973

227,785

ENCLOSURE FOR A RADIO OR TELEVISION ANTENNA

Raymond Kaysen, Glenside, Pa., assignor to
RCA Corporation

Filed Aug. 11, 1972, Ser. No. 279,864

Term of patent 14 years

Int. Cl. D14—03

U.S. Cl. D26—14 F

Fig. 1.

Fig. 2.

Fig. 3.

Fig. 4.

FIG. 1 is a perspective view of an enclosure for a radio or television antenna, showing my new design,

FIG. 2 is a side elevation thereof,

FIG. 3 is a top plan view thereof,

FIG. 4 is a bottom view thereof.

I claim:

The ornamental design for an enclosure for a radio or television antenna, as shown and described.
